(57) **CLAIM**

I claim the ornamental design for the combined folding door jamb and end panel, as shown and described.

DESCRIPTION

FIG. 1 is a front elevational view of the combined folding door jamb and end panel in an open configuration. The rear view of the folding door shown in FIG. 1 being a mirror image of the front view.

FIG. 2 is an enlarged front view of the combined folding door jamb and end panel taken from the upper right portion in FIG. 1.

FIG. 3 is a bottom view of the folding door shown in FIG. 1. FIG. 4 is a top view of the folding door shown in FIG. 1. FIG. 5 is a left side view of the folding door shown in FIG. 1. FIG. 6 is a right side view of the folding door shown in FIG. 1.

FIG. 7 is a front elevational view of the combined folding door jamb and end panel in a closed configuration. The rear view of the closed folding door shown in FIG. 7 being a mirror image of the front view.

FIG. 8 is an enlarged front view of the combined folding door jamb and end panel taken from the upper portion in FIG. 7.

FIG. 9 is a bottom view of the closed folding door shown in FIG. 7.

FIG. 10 is a top view of the closed folding door shown in FIG. 7.

FIG. 11 is a left side view of the closed folding door shown in FIG. 7; and,

FIG. 12 is a right side view of the closed folding door shown in FIG. 7.

The broken lines showing castors and mini slats are for illustrative purposes only and form no part of the claimed design. The broken away sections illustrate indefinite length of the claimed design.
